UNITED STATES PATENT OFFICE.

WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

1,411,024.

Specification of Letters Patent. Patented Mar. 28, 1922.

Application filed June 13, 1919. Serial No. 303,913.

To all whom it may concern:

Be it known that I, WILLIAM F. HELMOND, a citizen of the United States, residing in Hartford, in the county of Hartford and State of Connecticut, have invented certain new and useful Improvements in Typewriting Machines, of which the following is a specification.

This invention relates to the means whereby 10 by the type-keys effect letter-feeding movements of the carriages of typewriting machines, and, as claimed herein, has principally to do with the escapement mechanism, and particularly with the mounting of the 15 escapement wheel.

The features of the invention disclosed herein relating more particularly to the improved construction and mounting of the universal bar which transmits the movements of the keys to the letter-feeding dogs, and the improvements in means whereby the type-bars of the machine may be inserted and removed, are not claimed herein, and these features have been made the subject 25 of a divisional application, Serial No. 371, 312, filed April 5, 1920.

Typewriters are manufactured with a variety of styles of types, some type faces being small and requiring fine letter-feeding 30 movements of the carriage, and other type faces being large and requiring greater letter-feeding movements. Accordingly, the carriage escapement wheel may be provided with any appropriate number of teeth. It 35 is sometimes desired to increase or diminish the extent of letter-feeding movement of the carriage, and for this purpose another escapement wheel must be substituted, and it is one of the objects of the invention to 40 facilitate such substitution, and make the escapement wheel readily detachable from and replaceable in the machine. According to the present improvements, the escapement wheel is mounted upon a ball bearing in 45 such a manner that the wheel, the ball bearing and the usual pinion form a unit, which may be manufactured separately and set in place upon the machine. There are two sets of bearing balls running in ball cups formed 50 in the ends of a removable bushing, and cones for the balls are mounted upon a tube which is headed to retain the cones. This tube is carried by an axle which also carries

the pinion, the latter connected by the usual pawls to the escapement wheel, the axle 55 being readily removable from the tube.

Other features and advantages will hereinafter appear.

In the accompanying drawings,

Figure 1 is a central sectional side view 60 of an Underwood typewriting machine, illustrating the present improvements.

Figure 2 shows part of the devices seen at Figure 1, and illustrates the method of removing a type-bar from the machine. 65

Figure 3 is an enlarged detail of a conical pivot and a fitting therefor in the arm of a universal bar frame.

Figure 4 is a perspective view of the dog-rocker. 70

Figure 5 is an enlarged view of a stop-screw, seen at Figure 4, for arresting the stepping dog.

Figure 6 illustrates details of a stop-lever which is movable to permit the operation 75 seen in Figure 2.

Figure 7 is an enlarged perspective view of a conical pivot for the rocking frame which carries the universal bar, showing the arbor or mount for said pivot and its ad- 80 justing head and locking pin.

Figure 8 is a rear view of the escapement wheel and the escapement mechanism.

Figure 9 is a sectional view, taken about centrally of Figure 8. 85

Figure 10 shows details of the escapement wheel and its axle.

Keys 20 depress levers 21 to operate bell-cranks 22 to swing type-bars 23 up against the front of a platen 24, as is common in the Underwood machine; said platen being mounted upon a carriage 25 running on tracks 26, 27. A carriage rack 28 meshes with a pinion 29 that is connected to an escapement wheel 30, for controlling the letter-feeding movements of the carriage, the latter being driven by a spring barrel 31 under control of the escapement wheel. The movements of the escapement member or wheel are controlled by a rocker 32, having a rigid 90 detent dog 33 and a pivoted stepping dog 34, the latter normally meshing with the wheel and being held by a fixed stop formed on the dog-rocker 32; and movements are imparted to the dog rocker by a striker 35, which is 95 carried by a frame 36, the latter comprising 100 105

a universal bar 37, operable by heels 38 upon the type-bars. The universal bar 37 is concentric with the wire 39, upon which the type-bars are shown as pivoted.

5 At the depression of any key, its bell-crank 22 is operated, and the type-bar 23 swung up to the printing point, pressing back the universal bar 37 and frame 36, and by means of the striker 35 pressing the dog 34 rocker back, so that the stepping dog 34 thereon escapes from the wheel 30, and the rigid detent dog 33 is carried into mesh with the wheel. The dog 34 is swung by a spring 40 to a point opposite the next notch in the 10 escapement wheel 30. Upon relief of the key from pressure, it is returned by a spring 41; the type-bar returns to normal position, and the universal bar is returned by a spring 42. The spring 40, which is connected to 15 the stepping dog 34 and to a stationary frame part of the machine, as is shown most clearly in Figure 1, operates also to return the dog rocker to the normal Figure 1 position.

20 25 The ribbon vibrator comprises a lever 43 engaged by an actuator 44, which is mounted upon the universal bar frame 36. The lever 43 is connected to vibrate a ribbon carrier 45, as usual in the Underwood typewriter. 30 This universal bar frame 36 has at its rear ends opposite arms 46, 47, which are pivoted upon upright guide arms 48, 49; the frame 36 being guided at its front end in the usual manner by a tongue 50 working in the type-bar segment 51. These arms rise from a 35 rock shaft 52, which is pivoted between uprights 53, 54, forming part of a general framework for the escapement mechanism.

The desired alignment of the universal 40 bar 37 is obtained by providing for bodily adjustment of the rocking guide frame 48, 49, 52. To this end, the rocking frame is mounted upon pivots 55, 56, which are relatively adjustable laterally in a manner to 45 displace one side of the rocking frame either forwardly or backwardly of the machine. The pivot 55 is in the form of a screw having a conical point, which fits in a bearing in one end of the shaft 52; the arbor or 50 mount 56 having a conical point 57, which fits in a similar bearing in the opposite end of the rock shaft 52. The pivot 55 may be stationary, except that it may be shifted endwise to adjust or take up play of the rock shaft 52; but the pivot point 57 is adjustable forwardly and backwardly; the arbor 55 being for this purpose mounted eccentrically of the pivot point 57. The pivot 57 should be at its topmost position, as in Figure 9, and may be secured against rotative 60 displacement by a locking pin 58, which may enter any of several notches 59 in a head 60 provided upon the arbor or shaft 56; said pin fixed at 61 in the casting 54. If, however, 65 the universal bar 37 should be found to oper-

ate differently at one end from the other, this difficulty can be corrected, by first taking out the arbor or shaft 56 and turning it so as to shift the pivot 57 either forwardly or backwardly, and then restoring said arbor, thereby displacing this end of the rocking frame 48, 49, 52, and hence swinging the frame 36 and universal bar 37 horizontally until the front or active edge of said universal bar is exactly parallel with the plane of the 75 pivot wire 39; the pin 58 now occupying another notch 59, to re-lock the arbor 56 against displacement. A set screw 62 may also be provided for the pivot or eccentric 56, to hold it where adjusted endwise in connection 80 with the opposite pivot 55. It thus becomes practicable and simple to secure accuracy of movement not only of the ribbon-vibrator, but also of the feed-dogs.

The arms 48, 49 may be provided with 85 gudgeons or pivots, one of which, 63, is threaded so as to be adjustable, and is secured by a set screw 64 and cone-pointed at 65, Figure 3, to fit in a conical hole 66, made in the arm 46. The screw 64 may be loosened, 90 and the pivot 63 screwed out to take up the shake, and the screw 64 then tightened. In arm 49 is forced a companion pivot or gudgeon 63^a, to fit in a conical hole made in arm 47. This construction permits the pivot 95 shaft to be dispensed with, which usually extends from arm 46 to arm 47 and renders the feeding dogs inaccessible.

The detent dog 33 and the stepping dog 34 are carried upon the rocker 32. Said 100 rocker may be journaled upon adjustable pivots 67 secured by set screws 68. The universal-bar frame striker 35 engages the end of a screw 69, which is threaded into the upper portion of the dog rocker 32; the screw being adjustable to secure fine variations in the timing of the rocker action. The dog rocker is returned by the spring 40 to normal position, the lower end of the rocker engaging the head of a stop screw 70 110 threaded into the framework. At its lower end, the rocker also carries an adjustable screw 71, which strikes against a stop 72 to limit the initial movement of the rocker. This stop 72 is pivoted upon a screw 73, and 1 has a handle 74, whereby it may be swung out of the path of the screw 71, to permit additional movement of the dog rocker and universal-bar frame 36 when it is desired to detach any type-bar from the machine, Figure 2, said stop 72 being returned by a spring 75 against a stop pin 75^a. A back-check pawl 75^b is also pivoted upon the dog rocker.

The spring 40 not only returns the dog rocker, but also vibrates the stepping dog 34 when the latter escapes from a tooth of the escapement wheel 30. The stepping movement of the stepping dog is limited by the tapered or beveled face of a cone-headed ad-

justable screw 76. This adjustable screw stop is placed directly upon the dog rocker 32, so that it becomes shifted together with said rocker whenever the pivot pins 67 are 5 re-adjusted, so that the re-adjusting of said pins 67 does not make it necessary separately to re-adjust the screw 76. Moreover, this screw stop can be placed near to the pivot of the stepping dog 34, thus decreasing the 10 noise of operation. Also, by reason of the fact that the cone-headed dog-adjusting stop-screw 76 is threaded into the dog-rocker 32 from the back thereof, parallel to the pivotal axis of the stepping dog 34, with its 15 head end exposed at the rear of the machine, as clearly appears in Figure 8, this screw is at all times accessible for adjustment, thereby to vary the forward throw of the stepping dog 34 when this dog is released from the 20 escapement wheel 30.

The escapement wheel 30 is journaled in a boss 77 at the top of the fixed frame 53, 54. In a bearing opening in said boss is removably fitted a bushing 93, in the ends of which 25 are formed cups 78 for two rows or sets of bearing balls 79. Cones 80 and 81 co-operate with the cups 78 to form raceways for the sets of balls. These cones are mounted upon a tube 82, which at its inner end is headed 30 at 83, and at its outer end is turned outwardly or rolled over at 84, to confine the outer cone 80 against the balls; a space 85 being left between the cones to permit them to be drawn together to compensate for 35 wear. The tube 82 may fit tightly but removably upon an axle 86; and a screw 87 threaded into the outer or rear end of said axle may clamp a plate or washer 88 against the end of the tubular retainer 82, holding 40 the same against the face of the wheel 30, and also drawing a shoulder formed by an enlarged portion 89 of the axle against the front face of the wheel. This enlarged portion 89 serves as a bearing or pivot for the pinion 29, which is confined thereon by the 45 head of a screw 91 threaded into the end of the axle part 89. The usual pawls 92 are pivoted upon the face of the wheel, and form a clutching device to engage the pinion 29, 50 which is loose upon the bearing 89. It will be seen that the escapement wheel and pinion may be manufactured as a unit, together with the pawls, the axle, and the bushing 93 having the other ball-bearing parts therein. 55 The bushing 93 may be removably retained in place by a set screw 94. By removing the screw 91 the pinion 29 may be readily withdrawn and another one substituted. The shaft 86, 89 may be readily detached, leaving 60 the bushing 93 and other parts of the ball-bearing in the machine. The escapement wheel 30 may be removed by removing either the axle 86 or the bushing 93 together with the parts carried thereby.

35 Variations may be resorted to within the

scope of the invention, and portions of the improvements may be used without others.

Having thus described my invention, I claim:

1. The combination of an escapement 70 wheel, and a ball-bearing device for said escapement wheel, said parts forming a unit, the ball-bearing device comprising a bushing, cones co-operating with the bushing, bearing balls interposed between the cones 75 and the bushing, and a tube on which said cones are mounted, said tube being headed over the cones.

2. The combination of an escapement wheel, and a ball-bearing device for said escapement 80 wheel, said parts forming a unit, the ball-bearing device comprising a bushing, cones co-operating with the bushing, bearing balls interposed between the cones and the bushing, a tube on which said cones are mounted, 85 said tube being headed over the cones, and a detachable wheel axle on which said tube is mounted.

3. The combination of an escapement wheel, and a ball-bearing device for said 90 escapement wheel, said parts forming a unit, the ball-bearing device comprising a bushing, cones co-operating with the bushing, bearing balls interposed between the cones and the bushing, a tube on which said cones 95 are mounted, said tube being headed over the cones, a wheel axle on which said tube is mounted, and means on the end of said axle for confining the cones.

4. The combination of an escapement 100 wheel, a relatively movable pinion, a clutching device between the escapement wheel and the pinion, and a detachable ball-bearing device for said escapement wheel, said parts forming a unit.

5. The combination of an escapement wheel, a relatively movable pinion, a clutching device between the escapement wheel and the pinion, a detachable ball-bearing device for said escapement wheel, said parts forming a unit, the ball-bearing device comprising 110 a bushing, cones co-operating with the bushing, and bearing balls interposed between the cones and the bushing.

6. The combination of an escapement 115 wheel, a relatively movable pinion, a clutching device between the escapement wheel and the pinion, a detachable ball-bearing device for said escapement wheel, said parts forming a unit, the ball-bearing device comprising a bushing, cones co-operating with the bushing, bearing balls interposed between the cones and the bushing, and a tube on which said cones are mounted, said tube being headed over the cones.

7. The combination of an escapement wheel, a relatively movable pinion, a clutching device between the escapement wheel and the pinion, a detachable ball-bearing device for said escapement wheel, said parts form- 130

5. said cones are mounted, said tube being headed over the cones, a wheel axle on which said tube is mounted, and means on the end of said axle for confining the cones.

8. The combination of an escapement 10 wheel, a relatively movable pinion, a clutching device between the escapement wheel and the pinion, a detachable ball-bearing device for said escapement wheel, said parts forming a unit, the ball-bearing device comprising a bushing, cones co-operating with the bushing, bearing balls interposed between the cones and the bushing, a tube on which said cones are mounted, said tube being headed over the cones, a wheel axle on which said 20 tube is mounted, and means on the end of said axle for confining the cones, said axle having an enlargement forming a pivot for said pinion.

9. The combination of an escapement 25 wheel, a relatively movable pinion, a clutching device between the escapement wheel and the pinion, a detachable ball-bearing device for said escapement wheel, said parts forming a unit, the ball-bearing device comprising a bushing, cones co-operating with the bushing, bearing balls interposed between the cones and the bushing, a tube on which said cones are mounted, said tube being headed over the cones, a wheel axle on which 30 said tube is mounted, means on the end of said axle for confining the cones, said axle having an enlargement forming a pivot for said pinion, and means upon the end of said enlargement for confining said pinion.

40 10. In a typewriting machine, an escapement wheel, a ball-bearing equipment therefor comprising a bushing removably inserted in a bearing in the framework, cones co-operating with the bushing, bearing balls

interposed between the cones and the bushing, and means for confining said cones to said escapement wheel; the wheel, cones, balls and bushing forming a unit detachable from and attachable to the machine.

11. In a typewriting machine, an escapement wheel, a ball-bearing equipment therefor comprising a bushing removably inserted in a bearing in the framework, cones co-operating with the bushing, bearing balls interposed between the cones and the bushing, 55 means for confining said cones to said escapement wheel; the wheel, cones, balls and bushing forming a unit detachable from and attachable to the machine, and a pinion mounted upon said unit and having a clutch 60 connection to said wheel; said pinion being detachable from said unit.

12. In a typewriting machine, an escapement wheel, a ball-bearing equipment therefor comprising a bushing removably inserted 65 in a bearing in the framework, cones co-operating with the bushing, bearing balls interposed between the cones and the bushing, means including a detachable shaft for confining said cones to said escapement 70 wheel; the wheel, shaft, cones, balls and bushing forming a unit detachable from and attachable to the machine, and a pinion mounted upon said unit and having a connection to said wheel; said pinion being detachable from said unit.

13. In a typewriting machine, in combination, a framework provided with an opening forming a supporting bearing, a unitary detachable anti-friction bearing device removably insertable in said bearing opening, an escapement wheel, and a detachable axle for the escapement wheel removably insertable in said bearing device.
